UNITED STATES PATENT OFFICE.

HOELL B. SMITH, OF TREMONT, ILLINOIS.

IMPROVEMENT IN PLOWS.

Specification forming part of Letters Patent No. 127,110, dated May 21, 1872.

To all whom it may concern:

Be it known that I, H. B. SMITH, of Tremont, in the county of Tazewell and State of Illinois, have invented a new and valuable Improvement in Plows; and I do hereby declare that the following is a full, clear, and exact description of the construction and operation of the same, reference being had to the annexed drawing making a part of this specification, and to the letters and figures of reference marked thereon.

Figure 1 of the drawing is a representation of a side view of my plow. Fig. 2 is a bottom view of my plow. Fig. 3 is a land-side view of the same.

The object of this invention is to simplify the construction of plows, and to lessen their draft by decreasing friction and otherwise; and it consists in the construction and novel arrangement of the several parts hereinafter described.

In the accompanying drawing, the letter A designates a mold-board, which may have the usual concave form. A' represents the share, which also may be of the usual shape; B, the share-bar or land-side, a curved bar corresponding to the bend of the mold-board and share. To the upper edge of this share-bar the mold-board and share are secured. The under edge is also curved upward, and is parallel or nearly so with the upper edge. The length of the share-bar is sufficient to allow it to extend a little above the ground in the deepest plowing. The lower or point end is forged down gradually, so that it shall be flattened from above downward, in the usual form for welding on the share. C represents the standard, of a curved form flattened from side to side, and having its upper and under edges parallel or nearly so. The lower end of this standard is flattened from above downward, as at z, and is curved somewhat obliquely to correspond with the bend of the share and mold-board. This bar C therefore serves not only as a standard, but also as a connecting-strap to secure the share and mold-board together.

The position of the standard with reference to the share-bar will usually be a little inclined laterally, the mold-board and share

being secured to said standard at such points as will best serve to secure a center draft.

In small plows the standard will approach the share-bar very closely, but in larger ones, there will be a tapering space between, which should be filled with a tapering block, y, of wood or metal. The former is preferable on account of its lightness. This block may be secured by passing through it the bolt which connects the share-bar at its upper end with the standard.

d represents the connecting-strap, by means of which the mold-board and share are secured together at their rear ends. This strap has an oblique position, as shown in the drawing, being designed to form an angle of about forty-five degrees with the plow-standard. It fits closely and is secured to the under sides of the share and mold-board; and, at its upper end, is secured to the standard by the bolt d, which fastens said standard to the share-bar. It may be otherwise secured, if found desirable.

A plate, E, is sometimes used to strengthen the connection, said plate being secured to or under the end of the standard C. Both the bar d' and plate E serve as braces for the mold-board and share. B' represents the colter, which consists of a smooth plate having its under edge curved to correspond with the curve of the share-bar. The upper edge is formed with a convex curve very much inclined, and extending somewhat above the inner surface of the mold-board and share. It is secured to the share-bar by means of countersunk screws or bolts, and is designed to present a smooth and polished surface to the land-side of the furrow. This colter is used especially with gang-plows. For the single plow I usually secure a triangular colter, such as is represented at G, to the beam in front of the plow.

By the above-described construction it is designed to relieve the plow from much extra and, it is thought, unnecessary draft, while its working power is not diminished. The parts are constructed with a view to lightness and strength, while no portion is allowed to come in contact with the ground, except those

which are necessary to form the furrow, and to turn and pulverize the soil, which parts are provided with bright surfaces and keen edges.

I claim as my invention—

The plow herein described, consisting of the curved share-bar B, curved standard C, curved brace d', mold-board A, share A', and landside plate B' forming the colter, substantially as specified.

In testimony that I claim the above I have hereunto subscribed my name in the presence of two witnesses.

HOELL B. SMITH.
